[57] CLAIM

The ornamental design for a display and dispenser bin for edible products such as nuts, candies and the like, as shown.

DESCRIPTION

FIG. 1 is a perspective view of a display and dispenser bin for edible products such as nuts, candies and the like showing my new design;

FIG. 2 is a front elevational view thereof;

FIG. 3 is a bottom plan view thereof;

FIG. 4 is a top plan view thereof;

FIG. 5 is a rear elevational view thereof;

FIG. 6 is a perspective view of a modified embodiment of the display and dispenser bin for edible products such as nuts, candies and the like shown in FIG. 1;

FIG. 7 is a front elevational view thereof;

FIG. 8 is a top plan view thereof;

FIG. 9 is a left side elevational view thereof;

FIG. 10 is a rear elevational view thereof; and

FIG. 11 is a bottom plan view thereof.
